UNITED STATES PATENT OFFICE.

JOSEPH J. DONEGAN, OF KANSAS CITY, MISSOURI.

LAWN-SPRINKLER.

1,377,409.

Specification of Letters Patent. Patented May 10, 1921.

Application filed March 2, 1920. Serial No. 362,824.

To all whom it may concern:

Be it known that I, JOSEPH J. DONEGAN, a citizen of the United States, and resident of Kansas City, county of Jackson, State 5 of Missouri, have invented a certain new and useful Improvement in Lawn-Sprinklers, of which the following is a complete specification.

The present invention pertains to sprinkling devices, and aims to devise a novel form of lawn or garden sprinkler having an improved arrangement and construction of parts and providing a simplified and more efficient device of this character.

15 One of the objects of the invention is to provide a lawn or garden sprinkler having a water wheel actuated from a jet nozzle, and means actuated by the movement of said wheel for producing a travel of said 20 wheel bodily about a vertical axis. For this purpose I have devised an improved bearing structure for journaling the parts of the device for said movement or travel about a vertical axis, the said axis coinciding with the axis of the water connection.

A further feature of the improvement comprises an improved coupling device adapted to form the connection between the water hose or conduit and the sprinkler 30 device, and having provision also for the attachment of supporting legs for the suitable support of the device in operative position.

It is further sought to devise an improved arrangement of the gear connection between 35 the water wheel and the bearing structure whereby the water wheel and the jet nozzle member are actuated about a vertical axis.

Further features of the improvement will appear in the course of the detailed description, which will now be made with reference to the accompanying drawing illustrating one form of construction which I have devised for embodying the invention after which the novel features therein will 45 be set forth in the appended claims.

In the drawing:

Figure 1 is a view in elevation showing a lawn or garden sprinkler constructed in accordance with the present invention;

50 Fig. 2 is an enlarged elevation, with parts of the device broken away and in section;

Fig. 3 is a plan view of the same, with the cap member of one of the gear housings omitted;

Fig. 4 is a section taken on the line 4—4 55 of Fig. 2; and

Fig. 5 is an enlarged sectional detail view of the tip of the nozzle member.

Referring now to the said drawing in detail, this illustrates the improved sprinkler 60 device as adapted to be connected to a hose 6 or other water conduit member, terminating in a nipple or pipe section 7 adapted to be received in a coupling member 8, which member is formed with a plurality of 65 inclined recesses or sockets 9. These sockets 9 are designed for the reception of the upper ends of a plurality of legs 10 for supporting the sprinkler device in upright and operative position, the said upper ends of 70 the legs 10 being clamped in the sockets 9 by means of clamping screws 12, while the lower ends of the legs are tapered or pointed, as shown in Fig. 1, for adapting the same to be firmly embedded in the soil, in 75 an obvious manner.

Threaded into a recess 14 in the upper end of the coupling member 8 is the lower end of a tubular bearing member 15, having its upper end fitted centrally to a fixed 80 or stationary gear wheel 16 (see Fig. 2). Within the tubular bearing member 15, is a rotating sleeve 17 forming a continuation of the bore of the coupling member 8 and of the hose connection 7, the lower end of 85 said sleeve having a flange 18 fitting within the base of the recess 14 and abutting against the lower end of the bearing 15, while packing material 19 is interposed between the upper end of the bearing 15 and 90 the gear wheel 16 and around the sleeve 17. To the upper end of the sleeve 17 is attached a pipe connection 20 provided with a suitable nozzle tip 21, said pipe connection 20 being attached to the sleeve 17 by means 95 of a suitable gland or nipple 22 embracing said pipe connection and fitting within the upper end of the sleeve 17, as shown in Fig. 2.

Also secured to the upper end of the sleeve 100 17 is a supporting structure which comprises a housing member 24 secured to said sleeve by means of a clamping screw 25, the said housing member having formed, near the margin thereof, an upright tubular 105 bearing post 26 for the journaling of an upright shaft 27, the lower end of which shaft is provided with a pinion 28 meshing

with the teeth of the gear wheel 16. At the upper end of the post 26 is formed a housing 29 which incloses a worm wheel 30 secured to the upper end of the shaft 27, the said housing 29 being provided with a suitable cap member 31 adapted to be retained in place by means of screws 32. At one side of the worm wheel 30 is journaled a horizontal shaft 33 having bearings in said 10 housing 29 and carrying a worm 34 meshing with the teeth of the worm gear 30. One of the outer ends of the shaft 33 carries a water wheel 35 having its vanes 36 extending in such a direction that the wheel will be 15 actuated by impact of the water jet from the nozzle 21 upon said vanes of the wheel 35.

It will thus be apparent that I have devised a novel and improved form of construction for carrying out the proposed object of the invention. The wheel 35 is so mounted that on rotation thereof the path of the vanes 36 intersects the path of the jet from the nozzle 21 and obviously since the axes of said wheel and the sleeve 17 are 20 relatively fixed, this relation between the wheel 35 and the nozzle 21 will be maintained constant. As said wheel rotates under the action of the jet from the nozzle the above described gear connections between 30 the wheel and the fixed bearing 15 will obviously impart a bodily travel of the wheel and its described supporting structure about the axis of said fixed bearing 15, the object of which, of course, is to distribute 35 the spray from the sprinkler device over a considerable area of which the said device is the center. I deem the present construction and arrangement of the supporting structure for the nozzle and wheel and the gear 40 connection therebetween to be a material improvement over the types of construction heretofore employed for producing a travel of the water wheel in a path about a vertical axis, a more effective action being obtained 45 by alining the hose connection with the nozzle pipe 20 and carrying the same directly through the axis of the vertical bearing. A very simple and advantageous means is afforded by the present device for the attachment 50 of the supporting legs by securing these to a coupling member forming the

connection between the water conduit and described bearing structure.

While I have shown and described what I now regard as the preferred form of embodiment of the improvement, I desire to reserve the right to make such changes as may fairly fall within the scope of the appended claims.

What I claim is:

1. A lawn sprinkler comprising a vertical fixed tubular bearing, a sleeve rotating within said bearing and provided with a water connection at its lower end and a nozzle at its upper end, a stationary gear fixed to the upper end of said bearing, a water wheel provided with a supporting structure carried by said sleeve for maintaining said wheel in position to be actuated by the jet from said nozzle, said structure being formed with a housing portion for inclosing said gear, a vertical shaft journaled in said supporting structure and provided with gear connections to said wheel, and a gear secured to the lower end of said shaft within said 75 housing and in meshed relation with said fixed gear.

2. A lawn sprinkler comprising a vertical fixed tubular bearing, a sleeve rotating within said bearing and provided with a water connection at its lower end and a nozzle at its upper end, a stationary gear fixed to the upper end of said bearing, a water wheel provided with a supporting structure carried by said sleeve for maintaining said wheel in position to be actuated by the jet from said nozzle, said structure being formed with a housing portion for inclosing said gear and with a tubular bearing post at the outer edge of said housing, a vertical shaft journaled within said bearing post and provided with a gear secured to the lower end thereof within said housing and in meshed relation with said fixed gear, gear connections between said wheel and the upper end of 90 said vertical shaft, and a housing member carried by the upper end of said bearing post and inclosing said gear connections.

In witness whereof I hereto affix my signature.

JOSEPH J. DONEGAN.
